CLAIM

The ornamental design for a showerhead, as shown and
described.

DESCRIPTION

In a preferred embodiment, the nature of this product is a
showerhead, such as a hand shower, primarily useful for
washing the human body.

FIG. 1 is a right, top, front perspective view of a showerhead
according to our new design;

FIG. 2 is a front elevational view thereof;

FIG. 3 is a rear elevational view thereof;

FIG. 4 is a right side elevational view thereof;

FIG. 5 is a left side elevational view thereof;

FIG. 6 is a top plan view thereof; and,

FIG. 7 is a bottom plan view thereof.

The broken line representations in the figures are for the
purpose of illustration only, and form no part of the claimed
design.
